DESIGN FOR A SINK BRUSH

Clyde A. Porter, Aurora, Ill.

Application May 13, 1935, Serial No. 56,802

Term of patent 14 years

To all whom it may concern:

Be it known that I, Clyde A. Porter, a citizen of the United States, residing at Aurora, Illinois, post-office address 460 Grand Avenue, Aurora, Illinois, have invented a new, original, and ornamental Design for a Sink Brush, of which the following is a specification, reference being had to the accompanying drawing, forming part thereof.

Fig. 1 is a top perspective view of a sink brush, showing my new design.

Fig. 2 is a side elevation thereof.

The distinguishing features of my brush reside in the bristle holder and handle of the configura-

tions shown and having the bristles which slant downwardly toward the front and the sides of the bristle holder, and terminate at their free ends along a plane or straight line parallel to the bristle holder, the slant of the bristles along the front and sides of the bristle holder being of such angle that the bristles protrude in a horizontal direction to a substantial degree beyond the borders of the bristle holder.

I claim:

The ornamental design for a sink brush, as shown and described.

CLYDE A. PORTER.
